Re. 16,773

UNITED STATES PATENT OFFICE.

ANTONIN MONTEILHET, OF PARIS, FRANCE, ASSIGNOR TO SOCIÉTÉ ANONYME DES TELEGRAPHES EDOUARD BELIN, OF PARIS, FRANCE.

ELECTRIC TRANSMISSION ARRANGEMENT.

Original No. 1,411,366, dated April 4, 1922, Serial No. 785,920, filed May 6, 1913. Application for reissue filed May 4, 1925. Serial No. 28,000.

One of the difficulties met with in the long distance transmission of electric signals by overhead, underground and submarine lines is the capacity effect of these lines, which 5 capacity is sometimes very great so that continuous current in traversing them experiences a retardation which is often considerable.

The object of the present invention is the 10 employment of continuous wave alternating current of high frequency in all cases where this difficulty is met with, and particularly for the purposes of telegraphy, the transmission of pictures, and other analogous uses, 15 associated with an optical receiver, such as a mirror galvanometer, or an oscillograph, that is to say, a receiver which works with deflection of a luminous beam occasioned by 20 variations in the current traversing an arrangement placed in a suitable magnetic field, or any other galvanoscope having the same effect.

In view of the employment of alternating 25 current, capacity need no longer be taken into account; it is only necessary that the signals to be transmitted should occur at a frequency less than that of the alternation of current and that at the receiver, the optical arrangement should be of high sensitiveness 30 in order that there may not be any fear of trouble in connection with registering.

At the transmitting station the current is produced by an alternator working at a high and variable frequency and the continuous 35 wave current thus produced is sent either directly into the line, or into the primary of a transformer by means of which a high voltage is applied to the line.

It is pointed out that this arrangement is 40 quite distinct from the arrangement using pulsatory or oscillatory current for certain cases of syntonized transmissions.

The apparatus producing the signals will be in series with the primary or the second- 45 ary of the transformer.

In those cases where series of identical points are to be transmitted, it is sufficient for the speed of succession of these points to be less than the frequency of the alternating 50 current in order that trouble may not arise, but in certain cases it may be desirable to send into the line a current of variable intensity, the variations being produced, for

instance, by the insertion of resistances or by modifying the resistance of a microphone. 55 Disturbances at the receiving apparatus should theoretically be produced since during the return of the spot of light the resistance may have changed, but if the frequency is sufficiently high, especially in relation to the movement of the part which causes these disturbances, the symmetrical points will be lit up once or several times and the impression, either ocular or photographic, will be regular, that is to say, will 60 correspond to the variations produced by the transmitter.

Referring to the drawing—

Figure 1 is a diagrammatic view of a transmitting station employing a shunt connection. 70

Figure 2 is a similar view incorporating the principles of the Wheatstone bridge.

It is obvious that if the transmitter be of a kind such that its resistance is too small to exert a sufficiently strong action when connected in series with the line, a shunt connection could be used. For instance, when the variations in the resistance of a microphone due to pressure exerted upon its diaphragm produced in any suitable manner are employed at the transmitter the microphone will be connected in parallel with the primary of the transformer. 75

By this means the diagram forming 85 Figure 1 of the accompanying drawings is obtained. In this diagram A is the alternator, C the principal condenser, c' a variable condenser for the purposes of regulation, P, the primary, and T the secondary 90 of the transformer connected with the line. S and S' are variable resistances provided for purposes of protection and of regulation.

With this system there can be sent with a relatively small power (less than 1 kilowatt) 95 signals or current variations produced in the line by traversing of prints, printing blocks, etc., the transmission being effected to considerable distances and by the employment of cables, without the necessity for taking account of capacity. By reason of the damping action the frequency should be chosen as low as possible. 100

The arrangement is based on the Wheatstone bridge and is shown in Figure 2 of the 105 drawings. The two branches from one of

the terminals A' comprise respectively the microphone M and the regulatable resistance R. The primary P of the transformer forms the diagonal of the bridge.

5 From the other terminal A² start two branches, one formed of a high resistance e, and the other by a very low resistance which may even be a short circuit c, the connections themselves forming this low resistance. If, 10 in this arrangement, a balance has been obtained and pressure is exerted on the diaphragm of the microphone diminishing its resistance, the current will traverse the primary P in a fixed direction changing from 15 one value to a higher value. The first value could correspond to balance conditions that is to say, could be zero.

If now e and c are interchanged by a simple change-over device, as indicated, the balance conditions will be inverted, that is to say, the maximum current would traverse the primary and this current would diminish when pressure was exerted on the diaphragm. With continuous current the polarity will be opposite in the two cases, but this feature does not exist when working with alternating current. If then in the first case the opaque end of the scale of tints corresponds to the weakest current, then the 25 transparency will increase as the pressure on the microphone increases. In the second case the weakest current would correspond to the transparent part and the beam would be returned towards the opaque end of the 30 scale by pressing on the microphone, that is to say, the registered image would be the inverse of the first case. This results from the 35 operation of inverting the connections of c e without touching the scale of tints or any 40 of the regulating devices.

Having now particularly described and ascertained the nature of the said invention and in what manner the same is to be performed, I declare that what I claim is:

45 1. In telephotographic systems of transmission, sending apparatus having an alternating current system, a transformer in the alternating current system having one of the elements connected with the sending apparatus, a Wheatstone bridge connection including means for enabling the inversion of the image without changing the sending apparatus or the regulation thereof, and also including said sending apparatus, and a regulat- 50 ing resistance having on one side a very

high resistance, and a very low resistance on the other side, the primary of the transformer forming the diagonal whereby by interchanging the two elements in the second part of the bridge the balance conditions are 60 changed, and accordingly the direction of displacement of the luminous beam at the receiver is changed.

2. In facsimile transmission, the combination with a record to be transmitted of a 65 source of high frequency alternating current, a transformer having primary and secondary windings, a microphone including means to vary its resistance according to the record to be transmitted, and circuits connecting said elements whereby a decrease in resistance of the microphone causes a decrease in current supplied to the transformer, and vice versa.

3. In facsimile transmission, the combination with a record to be transmitted of a 70 source of high frequency alternating current, a transformer having primary and secondary windings, a modulating device for said source operated from the record to be 75 transmitted, and connected in a path in shunt with the primary winding, and a connection from said source to said primary winding whereby a change in impedance of the device causes a reverse change in current supplied to the transformer.

4. In facsimile transmission, the combination with a record to be transmitted of a 80 source of high frequency alternating current, a transformer having primary and secondary windings, a current modulating device adapted to have its impedance varied according to the record to be transmitted, means whereby a decrease in impedance of the device causes a decrease in current supplied to 85 the transformer and vice versa, and variable resistances between the source and said device.

5. In facsimile transmission, the combination with a record to be transmitted, of a 90 source of high frequency alternating current, a transformer having primary and secondary windings, a current modulating device responsive to the record, and means whereby the amplitude of the high frequency carrier current is modulated thereby inversely as the 95 current passing through the modulating device and vice versa.

In witness whereof I affix my signature.
ANTONIN MONTEILHET.
